PILFER-PROOF DISPLAY PACKAGES

Anton H. Heller, Levittown, N. Y.

Application October 30, 1951, Serial No. 253,863

6 Claims. (Cl. 206—45.31)

This invention relates to improvements in a knock-down display box and more particularly to a knockdown display box which is pilfer-proof and which is suitable for visibly displaying expensive textile fabrics such as stockings or handkerchiefs.

One object of this invention is a knock-down display box formed from one single blank, which can be folded and manipulated to form a box for containing and for visibly displaying a textile fabric with the displayed fabric secured between the folds of the display box in such a manner that said fabric cannot be removed from the display box without damaging either the fabric or the display box. The display box when assembled is so reinforced that it is too strong and rigid to bend, fold or crumple, and too large to be conveniently concealed upon or about the person.

Another object is a pilfer-proof display package.

Other objects will appear from the detailed description which follows.

In the drawing comprising four sheets of ten figures numbered Fig. 1 to 10, inclusive:

Fig. 1 is a plan view of the one-piece unit blank from which the knock-down display box is constructed.

Fig. 2 is a front view of the display package fully assembled to display a textile fabric with said fabric secured therein against pilfering.

Fig. 3 is a vertical cross sectional view taken along the line 3—3 of Fig. 2 looking in the direction of the arrows.

Fig. 4 is a horizontal cross sectional view taken along the line 4—4 of Fig. 2 looking in the direction of the arrows.

Fig. 5 is a perspective view showing the display packages nesting one within another to conserve storage space.

Fig. 6 is a plan view of a modified form of one-piece unit blank from which a modified form of my knock-down display box may be constructed.

Fig. 7 is a front view of the display package formed by folding said modified blank.

Fig. 8 is a vertical cross sectional view taken along the line 8—8 of Fig. 7 looking in the direction of the arrows.

Fig. 9 is a horizontal cross sectional view taken along the line 9—9 of Fig. 7 looking in the direction of the arrows; and

Fig. 10 is a side view showing the display packages nesting one within another to conserve storage space.

Like reference characters designate corresponding parts throughout the several figures of the drawing.

The blank 10 (Fig. 1) which is stamped from one piece of cardboard or corrugated or laminated kraft paper or the like of suitable weight and thickness, and which may be flame-proofed, consists essentially of two main adjoining sections, namely the fenestrated front section 20, and the back member or box bottom 40.

Attached to and forming a continuation of the front section 20 are two side sections 21 and 22 and a back section 35. The side sections 21 and 22 are separated from the front section 20 by the converging scored lines

2

23 and 24, and the outermost side sections 29 and 30 are separated from the side sections 21 and 22 respectively by the spaced parallel scored lines 27 and 28, which may be paired as at 25, 27 and 26, 28. Thus when side sections 21 and 22 are folded inwardly along the scored lines 23 and 24, and the outermost side sections 29 and 30 are folded outwardly and downwardly along the scored lines 27 and 28, or outwardly along the scored lines 25 and 26, and downwardly along the scored lines 27 and 28 when the scored lines are paired, the channelled sides 51 and 52 (Figs. 2 and 4) are erected to partially construct the upstanding frame (compare Figs. 2 and 4).

The outermost side sections 29 and 30 are also provided with longitudinally extending flaps or tabs 33 and 34 which can be folded along the scored lines 31 and 32 respectively to provide means for keeping the channelled sides 51 and 52 in an erect position when the frame of the display package is completely formed (compare Figs. 2 and 3).

The back section 35 is separated from the fenestrated front section 20 by the scored line 36, and the outermost back flap 39 is separated from the back section 35 as by the scored line 38 or by a pair of spaced parallel scored lines 37 and 38, so that when the back section 35 is folded inwardly along the scored line 36, and the outermost back flap 39 is folded outwardly and downwardly along the scored line 38, or outwardly along scored line 37 and then downwardly along the scored line 38 where paired score lines are provided, the channelled back frame 50 (Figs. 2 and 3) is erected to partially construct the upstanding frame.

The base or back member 40 enjoins and merges with the front section 20 either along the scored line 42, or along spaced parallel scored lines 41 and 42, so that when the blank 10 is folded crosswise first downwardly and then inwardly along the scored line 42, or downwardly along scored line 41 if paired lines are used, it will register beneath the fenestrated front section 20 to form the back or bottom of the display package (compare Figs. 3 and 4).

The back or base member 40 is provided on its free side edges with side sections 45 and 46, and on its free end edge with end section 48, said sections being respectively separated from said back member 40 by the scored lines 43, 44 and 47. When each of the said sections 45, 46 and 48, is folded downwardly along its associated scored line 43, 44 or 47 respectively, and the blank 10 is folded crosswise along the scored line 42 or along parallel scored lines 41 and 42 as previously described, the side sections 45 and 46, and the end section 48, register in the channels formed between folded sections 21 and 29, 22 and 30 and 35 and 39, respectively (compare Figs. 2 and 3), and the longitudinally extending flaps or tabs 33 and 34 register in the channel formed between back section 35 and end section 48 (see Fig. 3) to complete the upstanding frame structure which encloses the fenestrated front section 20 upon three sides at 50, 51 and 52 (Fig. 2) to form the display box portion of the display package. Side sections 45 and 46, and end section 48 are so proportioned that they do not engage the top of their respective formed channels (compare Figs. 3 and 4).

It will be seen that the upstanding frame thus consists of three frame members 50, 51 and 52 (Fig. 2), and that the side frame members 51 and 52 consist of three plies each, namely plies 21, 45 and 29 or plies 22, 46 and 30 (Fig. 4), and that the end frame member also consists of three long plies namely plies 35, 48 and 39 and the flaps or tabs 33 and 34 which are inserted between the plies 35 and 48 (Fig. 3).

Each triple ply frame member 50, 51 and 52 is secured against any risk of disengagement of its interlock-

ing plies in any preferred manner as by means of three spaced groups of fasteners which may be either rivets or wire staples 56, 56 and which pass through all three of the thicknesses or plies of the kraft paper or the like which form each of the frame members 50, 51 and 52 to lock the said frame members in position and to interbrace them by means of the flaps or tabs 33 and 34 (see Fig. 2).

The textile article 55 is displayed through the window opening 46'. The window opening may be artistically formed as with scallops 45', and is enclosed as by a sheet of cellophane 47' or other transparent film-like material secured to the inside of the window frame whereby a sufficient portion of the article is visibly displayed, so that a prospective purchaser may examine the quality, brandmark, size, and any other data carried by the textile article which may be visible through the cellophane window 47'. The window opening 46' extends through the fenestrated section 20 and is large enough to clearly display the merchandise but small enough to leave a wide border around the cellophane window 47' which border is strong enough at all points to prevent the display package from being folded or crumpled.

As best shown in Figs. 3 and 4 the marginal edges of the kraft paper surrounding the opening 46' in the fenestrated front section 20 and the back member 40, are drawn close together when the triple ply frame members 50, 51 and 52 are interlocked and are fastened as by rivets or wire staples 56, so that the fragile textile article 55, which may be a pair of silk or nylon stockings, is securely clamped by and between the peripheral marginal edges of the fenestrated front section 20 and the back member 40 in conjunction, so that if the cellophane window 47' is surreptitiously torn out the merchandise 55 cannot be removed through the opening 46' without tearing or otherwise rupturing the relatively fragile merchandise 55 which is held stretched taut by the clamping action effected by the marginal edges of fenestrated front section 20 and the back member 40 (compare Figs. 2, 3 and 4).

The scored lines 23, 24 which define the side edges of the fenestrated front section 20, and the scored lines 43, 44 which define the side edges of the back member 40 are formed along oppositely converging lines (see Fig. 1), so that when the blank 10 is folded along the scored lines 41 and 42, said blank tapers from the unframed front edge towards the frame member 50, and the taper is so proportioned that the overall width of the package measured along frame 50 from the outside of frame 51 to the outside of frame 52 is less than the width of the opening between the side frame members 51 and 52 at the front edge of the package. Thus the display packages 10, 11 and 12 may be nested one inside the other as best shown in Fig. 5 to conserve storage space when the merchandise is in storage awaiting shipment. This is an important advantage especially in department stores where storage space is frequently at a premium. Likewise by nesting the packages 10, 11 and 12, etc., one inside the other (Fig. 5), when the display packages are being prepared for shipment, a substantial saving in shipping space can be made.

In the modified form shown in Figs. 6 and 10, the display package 59 (Fig. 7) is completely framed in upon all four sides of the fenestrated front section 60. This result is accomplished by so shaping the blank (Fig. 6), as to furnish a fourth frame element consisting of the added sections 84 and 88 (compare Figs. 6 and 7). This fourth frame element is locked between the side frame elements 61 and 62 by an added pair of flaps or tabs 77 and 78 (compare Figs. 1 and 6).

Front section 60 (Fig. 6) is provided with a window opening 98 which may be artistically shaped at 99 but so as to leave a mat of substantial width around the window opening 98. The window opening may be covered by a cellophane window 100. Front section 60 is

separated from its side sections 61 and 62 by the scored lines 63 and 64, and either the scored lines 67 and 68 or the spaced pairs of parallel scored lines 65, 67 and 66, 68 if used, serve to mark off the outer flaps 69 and 70 from side sections 61 and 62. Scored lines 71, 72, 75 and 76 mark off the paired tabs 73, 74 and 77, 78 from the outer flaps 69 and 70.

Back section 79 is marked off by a scored line 80, and either the scored line 82 or the spaced parallel scored lines 81 and 82 if both are used mark off back fold 83 from back section 79. Inner central section 84 is marked off from front section 60 by scored line 85, and either the scored lines 87 and 90 or the pairs of spaced parallel scored lines 86, 87 and 89, 90 if paired scored lines are used, mark off outer central section 88 from inner central section 84 and from the base member 91. Base member 91 is provided with two side sections 92, 93 and an end section 96, and the said sections are marked off by the scored lines 94, 95 and 97 respectively. To effect correct registry of the several plies when folded, sections 92 and 93 are bevelled at 102 and 103 respectively.

The box is formed by folding the side sections 61 and 62 back, and inner central sections, 79 and 84, inwardly along the scored lines 63, 64, 80 and 85; then folding the flaps 69 and 70, back fold 83, and outer central section 88, outwardly and downwardly along the scored lines 67, 68, 82 and 87, or outwardly, along the scored lines 65, 66, 81 and 86, and then downwardly along the scored lines 67, 68, 82 and 87 when the paired scored lines are used, to form the four channelled sections of the frame assembly. The base member 91 may now be folded either along the scored line 90 or the scored lines 89 and 90 when both are used to position base member 91 beneath front section 60, and side sections 92, 93 and end section 96 may now be folded along scored lines 94, 95 and 97 to bring them into registry with the channels former by sections 61, 69; 62, 70; and 79, 83 (compare Figs. 8 and 9). The tabs 73, 74 enter the channel formed between back section 79 and end section 96, and the tabs 77, 78 enter the channel formed between inner and outer central sections 84 and 88 (compare Figs. 7 and 8). The pairs of rivets or wire staples 101, 101 are fastened through all three plies of the side frame members, and through all four plies of the front and back frame members to interbrace said members and completely assemble the frame and close the display package.

During the folding operation the merchandise 55 is inserted in the box so that when the folding operation is entirely completed and the rivets or staples 101, 101 are fastened in place, the merchandise 55 is effectively clamped between the front section 60 and the base member 91 around the entire peripheral marginal edge of the merchandise, so that while the merchandise 55 is effectively visibly displayed through the cellophane window 100, it can not be removed even though the cellophane window 100 is torn open, and the package is too rugged to be folded or crumpled, and is much too large to be conveniently concealed upon the person.

The frame is bevelled to enable the display packages to nest one above another Fig. 10 to conserve storage and shipping space.

While as shown in the drawings the crease lines between the fenestrated front sections of the blanks and their respective side and back sections, and the crease lines between said fenestrated front sections and the bottom members, are indicated as paired scored lines, it should be understood that each of said crease lines may consist of one scored line only rather than a pair of parallel scored lines.

To those skilled in the art the disclosure of my application will suggest other modifications and variations of my blank for a pilfer-proof box.

What is claimed is:

1. A display package comprising a rear section having upstanding frame members, a front section having upstand-

ing frame members, said front section being spaced slightly from said rear section and in overlying relation thereto, material to be displayed being disposed between said front and rear sections and substantially filling the space therebetween, a transparent window in said front section for receiving a portion of said material, said upstanding frame members of said front and rear sections being interlocked, said material being clampingly engaged by said front and rear sections.

2. The display package of claim 1, wherein said upstanding frame members of said front section include reversely folded portions, said upstanding frame members of said rear section being disposed within the confines of the upstanding frame members of said front section.

3. The display package of claim 1, wherein said front and rear sections have at least one pair of integral upstanding frame members.

4. The display package of claim 1, wherein certain of said frame members of one of said front and rear sections include reversely folded portions, certain of said frame members of the other of said sections being disposed within confines of said certain frame members of said one section, said front and rear sections have at least one pair of integral frame members.

5. A display package comprising a rear section having upstanding free members, a front section having upstanding frame members, said front section being spaced slightly from said rear section and in overlying relation thereto, material to be displayed being disposed between said front and rear sections and substantially filling the space therebetween, a transparent window in said front section for receiving a portion of said material, said

upstanding frame members of said front and rear sections being interlocked, said material being clampingly engaged by said front and rear sections, said window being of a size to resist passage of said material therethrough.

6. A pilfer-proof display package comprising a single sheet of material folded intermediate its ends to form overlying front and rear sections, said front section having opposite side edges and a free end, upstanding frame members along said side edges and free end, said rear section having opposite side edges and a free end, upstanding frame members along said side edges and free end of said rear section, said frame members of said front and rear sections being interlocked, said front and rear sections being slightly vertically spaced, material to be displayed disposed between said front and rear sections, a transparent window in said front section, said material underlying said window and being clampingly engaged by said front and rear sections.
